UNITED STATES PATENT OFFICE.

WILLIAM H. GREEN AND P. J. CLARK, OF MERIDEN, CONNECTICUT,
ASSIGNORS TO S. S. CLARK, OF SAME PLACE.

DESIGN FOR A CHANDELIER.

Specification forming part of Design No. 1,569, dated April 29, 1862.

To all whom it may concern:

Be it known that we, WILLIAM H. GREEN and P. J. CLARK, of Meriden, in the county of New Haven and State of Connecticut, have invented or produced a new and original Design for a Chandelier; and we do hereby declare that the following is a full, clear, and exact description of the same, reference being had to the accompanying drawings, making a part of this specification, in which—

Figure 1 is a side view of a chandelier, showing our design; Fig. 2, an enlarged detached section of one of the lamp circles or holders of the same; Fig. 3, a detached and enlarged section of the top piece or cap of the same.

Similar letters of reference indicate corresponding parts in the several figures.

A represents the rod by which the chandelier is suspended from the ceiling or wall, and B represents the central part of the chandelier, to which the brackets C C are attached. This central part B is formed at its upper part of a dome-shaped cap a, having an oval or egg-shaped pendant b, which is at the crown of an arch c. The arch c springs from two polygonal taper-pendants d d, scalloped, as shown, at e, and provided with bud-shaped terminals f. Underneath the arch c at each side of the egg-shaped pendant b there is a scroll g, the lower ends of which are connected by a semicircular string of beads h, provided at each end with a pendent tassel i. The

lower part of the egg-shaped pendant b has an urn j attached, which rests on a base k, is connected with the string of beads h at its center, and is provided with a pendent tassel l. At the under side of the scrolls g there are thin or narrow arches m m, connected by squares n n with the sides of the urn j.

D D represent the lamp circles or holders, the outer surfaces of which are provided with V-shaped ornaments o in relief, filled with cross-bars p, forming diamond-shaped fret-work, as shown more particularly in Fig. 2.

E represents the cap of the chandelier, which is at the upper part of the rod A. This cap is formed of a fluted base q, surrounded by a circular basin-shaped ornament composed of open scroll-work r, as shown clearly in Fig. 3.

The brackets C C and rod A form no part of the design.

What we claim as new, and desire to secure by Letters Patent, is—

The general configuration of the central part B, lamp circles or holders D D, and cap E, as herein shown and described, to form a new and original design for parts pertaining to a chandelier.

WM. H. GREEN.

P. J. CLARK.
